(57) **CLAIM**

(21) Appl. No.: **29/655,416**

The ornamental design for a positioning base for a socket holding frame, as shown and described.

(22) Filed: **Jul. 3, 2018**

DESCRIPTION

(51) LOC (12) Cl. **08-05**

FIG. 1 is a perspective view of a positioning base for a socket holding frame, showing my new design;

(52) U.S. Cl.

FIG. 2 is a front view thereof;

USPC **D8/366**

FIG. 3 is a rear view thereof;

(58) **Field of Classification Search**

FIG. 4 is a left side view thereof;

USPC D8/16, 18, 19, 33, 38, 363, 354, 349,

FIG. 5 is a right side view thereof;

D8/382, 356, 355, 330, 383, 370;

FIG. 6 is a top view thereof;

D6/684; D25/156

FIG. 7 is a bottom view thereof; and,

CPC A47F 7/0028

FIG. 8 is a perspective view of another embodiment thereof. The broken lines depict environmental subject matter, are for illustration only and form no part of the claimed design.

See application file for complete search history.
